UNITED STATES PATENT OFFICE

99,458

DESIGN FOR TEXTILE FABRIC

George H. Perkins, Wellesley, Mass., assignor to Powdrell & Alexander, Inc., Danielson, Conn., a corporation of Massachusetts

Application March 7, 1936, Serial No. 61,524

Term of patent 3½ years

To all whom it may concern:

Be it known that I, George H. Perkins, a citizen of the United States, residing at Wellesley, in the county of Norfolk, State of Massachusetts, have invented a certain new, original, and ornamental Design for Textile Fabrics, of which the following is a specification, reference being had therein to the accompanying drawing.

The drawing is a face view of a portion of the fabric showing my new design.

I claim:

The ornamental design for textile fabric, substantially as shown.

GEORGE H. PERKINS.
